UNITED STATES PATENT OFFICE.

HOWARD A. POST, OF WINFIELD, KANSAS.

FOOT-TREATING APPLIANCE.

1,315,035.

Specification of Letters Patent.

Patented Sept. 2, 1919.

Application filed August 24, 1918. Serial No. 251,277.

To all whom it may concern:

Be it known that I, HOWARD A. POST, a citizen of the United States, residing at Winfield, in the county of Cowley and State of Kansas, have invented new and useful Improvements in Foot-Treating Appliances, of which the following is a specification.

My present invention pertains to the treatment of the foot with a view to replacing misplaced bones and correcting what is popularly referred to as broken arches.

One object of my invention is to provide an appliance in the nature of a bone-pressing element, adapted for use at the bottom 15 of the foot, and of such character that the particular bone under treatment may be handled without interference from adjacent bones, and all of the misplaced bones of the foot may be individually treated until the 20 malformation is entirely overcome.

Another object of the invention is the provision of an appliance of such shape and character that the end stated may be attained without bruising or otherwise injuring the 25 flesh or muscles of the foot.

Another object is the provision of an appliance for the purpose stated equipped for attachment to the hand in such manner that all of the fingers of the hand are left free 30 for use in steadying and holding the foot during the application of the appliance to the particular bone that is under treatment.

Another object is the provision of an appliance equipped with attaching means of 35 such construction and arrangement that not only the fingers but also the thumb is left free for holding and steadying the foot while the appliance is correctly positioned relative to the individual bone to be replaced.

40 The invention contemplates the use of the appliance on either the right hand or left hand of the operator, the positioning and holding of the appliance under the foot and in proper arrangement relative to the bone 45 to be treated, and the utilization of sharp pressure by the operator with his other hand on the upper side of the foot to bring about replacing of the particular misplaced bone at the time under treatment.

50 With the foregoing in mind the invention in all of its details will be fully understood from the following description and claims when the same are read in connection with the drawings, hereby made a part of this 55 specification, in which:

Figure 1 is a perspective illustrative of

the preferred embodiment of my invention as the same appears when fastened upon the hand of an operator.

Fig. 2 is an enlarged longitudinal section 60 of the appliance and the attaching means, removed.

Fig. 3 is a perspective illustrative of a modification, in proper position upon the hand.

Fig. 4 is a rear elevation of the modification *per se*.

Similar numerals of reference designate corresponding parts in Figs. 1 and 2, and the same numerals with exponents designate 70 analogous parts in Figs. 3 and 4.

The salient feature of my invention is a contact piece 1 that is yielding and elastic in character and is therefore not likely to bruise or otherwise injure the flesh or 75 muscles of the foot incidental to the use of the appliance. In the embodiment shown in Figs. 1 and 2 the said contact piece 1, which may be of rubber, cork, felt, or other material compatible with its purpose, is carried 80 at the forward end of a thumb stall 2, and it is desirable that the said thumb stall be of such length and that it be so fastened to the hand that the extremity of the operator's thumb merely touches the forward 85 closed end of the stall. With a view to prolonging the usefulness of the device the forward end of the stall is preferably closed by a wall 3 which is adapted to isolate the thumb from the contact piece 1. The thumb 90 stall 2 may be made of light sheet metal or other appropriate material; and it is provided with a shank 4, adapted to rest as shown in Fig. 1, relative to the hand of the operator. At 95 the said shank is equipped with a headed protuberance, and to this latter is fastened, preferably in adjustable manner, a strap 6, preferably of leather, that is adapted to receive and rest on the base of the thumb in the manner 100 shown. Also carried by the shank 4 is a wrist strap 7 equipped with a buckle 8, and adjustable as to length to fit the wrists of different operators.

Manifestly the device described may be 105 expeditiously and easily fastened upon the hand of the operator in the manner shown in Fig. 1.

In the practical use of the device the contact piece 1 is pressed to the particular bone 110 to be treated or correctly positioned, and when this is done the fingers of the operator

which are left entirely free may be utilized to advantage in grasping and steadyng the foot and in enabling the operator to firmly hold the contact piece 1 in exactly the position that his judgment dictates for the best treatment of the bone to which the contact piece is presented. Then while holding the contact piece and the foot as stated, the operator thrusts or firmly presses the upper 10 side of the foot at the proper point with respect to the bone and the position of the contact piece 1, whereupon the bone will be moved or pushed back to its normal and proper position, and this without interference from any of the adjacent bones. This latter is due to the fact that the tip of the contact piece is presented to the under side of the foot, and there are no lateral projections on the contact piece such as are likely 15 to exert pressure against the portions of the foot at the sides of the particular bone that is being treated. In other words the contact piece 1 being small the said piece is presented to but one bone at a time, and hence the 20 individual treatment of the bones is rendered perfectly feasible. In the manner stated all of the misplaced bones of a foot are treated in proper succession and after repeated treatment in the manner indicated the malformation 25 of the fallen arch will be completely and permanently corrected.

The device may be used upon either hand of the operator and in either use the contact piece 1 is capable of being accurately positioned to treat any bone of the foot.

The embodiment illustrated in Figs. 3 and 4 is similar to that shown in Figs. 1 and 2 in that it comprises a contact piece 1^a having the same characteristics and the same capacity of function as the contact piece 1. The said contact piece 1^a, however, is affixed to the hand somewhat in the same manner as a sail maker's thimble. This will be fully understood when it is stated that the said contact piece 1^a is carried in a holder or stall 40 2^a, and the said stall, in turn, is carried by a palm piece 4^a, apertured at 5^a to receive the base of the thumb, and equipped with an elastic holding strap 7^a extending between 45 50 and connected to its ends and adapted in use to rest at the back of the hand.

The modification in Figs. 3 and 4 is pos-

sessed of all of the advantages ascribed to the embodiment shown in Figs. 1 and 2, and is also possessed of the advantage that follows from the thumb being left free so that it may be used in conjunction with the fingers in grasping and steadyng the foot and correctly positioning the piece 1^a and maintaining the same in the desired position.

The embodiments illustrated and specifically described constitute the best practical embodiments of my invention that I have as yet devised, but it is to be understood in this connection that I do not restrict myself to any particular mode of attaching the contact piece to or fastening the same upon the hand of the operator, nor do I desire to be understood as limiting myself to the fastening of the contact piece upon or the attachment of the same to the hand of the operator inasmuch as without departure from the principle of my invention the contact piece may be so equipped as to be firmly held by the hand.

Having described my invention what I claim and desire to secure by Letters-Patent is:

1. A foot treating appliance comprising a disk-like contact piece, of yielding material having a flat exposed side of a size to exert pressure against the under side of a single bone in the human foot without interference from an adjacent bone or bones, a rigid holder carrying and backing said disk-like contact piece, and means for fastening the said holder in position upon the hand of an operator, whereby the fingers of the operator may be used to grasp and steady the foot coincident with the application of the pad under and against the bone that is to be manipulated.

2. A device for the purpose described comprising a thumb stall, a yielding contact piece carried at the forward end of the stall, a stiff shank on the stall and extending rearwardly therefrom, a strap connected with the shank and adapted to receive the base of an operator's thumb, and a wrist strap also connected with the shank.

In testimony whereof I affix my signature.

HOWARD A. POST.
